UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

MULTIPLE-PLY-WEBS FOR TYPEWRITERS

Application filed September 4, 1930. Serial No. 479,639.

This invention relates to novel multiple-ply fan-folded work-webs usable in typewriting machines, such as illustrated, for example, in the patent to Wernery and 5 Smith, No. 1,132,055. The carbon-sheets interleave the web-plies, being held by transverse blades inserted from the side of the web.

The carbon-sheets are shifted backwardly 10 at intervals, preparatory to typing fresh portions of the web-plies.

It is desired to have certain of the web-plies of different color from others, which result is impracticable when all the plies are 15 made from a single longitudinally fan-folded web.

To avoid these and other objections, United States patent 1,400,631, granted to me December 20, 1921, discloses a multiple-ply 20 work web which may consist of a plurality of separate plies of different characteristics, having their side edges padded together at the side by an elastic adhesive material. The blades extend between the plies, being mounted 25 on the side of the web which is opposite from the glued edges. The padded side edge of said patent is somewhat thicker than the opposite edge, and the work-web therefore may tend to feed unevenly through typewriters having round platens.

The multiple-ply web of the present invention is made up of a number of loose plies of different colors or grades of paper. All the plies are printed first before being assembled into a composite web.

The printed plies may be delivered from spools, or from a printing press, but they are not immediately packed together, but are kept separated, while they are maintained in a zigzag relation, considerably longitudinally of the web. The appearance of the zigzag plies at this time would correspond to an ordinary fan-fold web that is opened up a little. One side edge of each ply is thus paired or contiguous to one side edge of the next ply. The other side edge of said next ply is paired with or contiguous to one side edge of the next ply, and so on throughout the set of plies.

Where the edges touch, adhesive is applied.

The webs may be kept separated in this zig-zag fashion while they are run through an oven, and the adhesive is dried, so that when the web is finally ready for shipment, it will be capable of opening up in zigzag 55 form, like any ordinary one-piece fan-fold web. The web may be packed, and may be cross-folded.

One of the advantages of the web is that half of the adhesive is used along one edge 60 of the composite web, and half along the opposite edge. A web made this way may run through the typewriter more successfully than were the adhesive all along one edge of the multiple-ply web.

Moreover, half of the carbon-blades can be set in from the right, and the other half can be set in from the left, which is an advantage because the web can be fully used by regularly equipped typewriters, which 70 would not be the case where all of the glued edges are on one side, and where consequently all of the carbon-blades would have to be set in from a single side of the web.

Other features and advantages will hereinafter appear.

In the accompanying drawings,

Figure 1 is a diagrammatic elevation to illustrate the printing of the plies, the application of adhesive to ply-edges in a manner to form joints at alternate edges of the web, the drying of the plies while they remain properly spread open, and the cross-folding of the completed web in a package 80 for shipment.

Figure 2 is a perspective view to show more clearly the parts at Figure 1.

Figure 3 is a perspective diagram of a bend in the guides over which the glued plies are run in drying.

Figure 4 is a fragment of a finished composite web.

The webs or plies 9, 10, 11, 12, 13, of which five are illustrated (although the product may comprise more than five plies), are passed simultaneously through a printing press comprising printing couples 14, whereby successive forms are printed, the forms upon each ply registering with those on the other plies. From the printing press, the 95

webs are led onto an apparatus, which pads one side edge of each interior ply to the adjacent side edge of the next overlying ply, and the other side edge to the adjacent side edge of the next underlying ply. This padding operation leaves the outer plies 9 and 13 each with one side edge padded and one side edge free. Thus there is provided by the padding operation an equivalent to a longitudinally fan-folded work-web.

10 The composite web can be opened up at each side for conveniently inserting the carbon-sheets. Each ply of the web may have different characteristics, such as color, quality or thickness.

15 One method of padding or fastening the plies together is illustrated, a suitable adhesive material being applied by rolls 15, 16 to the side edges of the plies. A separate roll 20 15 or 16 is provided for each pair of engaging or adhering side edges. Each roll 15 or 16 may be run in a suitable aperture in the bottom of a font 17 containing the adhesive, and the rolls and fonts may in some cases be provided with any suitable heating device (not shown) for keeping the paste or adhesive in a proper fluent condition. The adhesive may dry quickly.

If desired, the adhesive may be applied to 30 the edge of only one of the plies at each pair of edges.

All joined edges pass between pressure-roll couples 18, 19, below the fonts. The adhesive will stick the two plies together.

35 The length of one feed-roll or pressure-roll in each couple is much less than the width of the plies, because the roll must extend in between the plies whose opposite side edges are pasted together. The outer ends of a feed-roll couple may be arranged to not quite reach 40 the pasted edges, so that the adhesive material will remain only on the extreme edges of the engaging plies and the rolls will not tend to spread the adhesive across the faces of the plies.

45 The rolls may, however, press the pasted edges of the plies together, and stationary stripping or cleaning knives may be used for keeping the rolls clean from adhesive material.

Auxiliary feed-roll couples 20 for each 50 pair of plies may be provided above the pasters 15. All of the driving rolls 20 may be suitably connected with the couples 14 of the printing press, to secure proper speed of the composite web as it feeds to the padding apparatus.

When the adhesive 14^a on the side edges of the plies is dried, it forms an elastic film-like element, which fastens one edge to the adjoining edge in a way that the plies may be readily opened up.

The adhesive is applied in usual liquid form, and it is desirable that each pair of adherent edges be kept apart from the other

pairs until the adhesive has dried and ceased to be sticky.

To accomplish this result, I provide guides for the plies. These guides or separators 21 may resemble thin prisms or wedges, each 70 separating the adjoining plies. The thin edge of a guide-member between two plies is disposed toward the adherent edges.

To expedite the drying of the sticky adhesive, the composite web, while still held slightly opened, is passed through a drying oven 22. To conduct the composite web into the oven, and through it and out again, the web may be made to take a tortuous path, if 80 desired.

To turn the moving multiple-ply longitudinally fan-folded web, it is desirable to have the adherent plies lie as closely against each other, facewise, as is practicable, without bringing the pasted and sticky side edge couples into undesired contact. For this reason the guide-members are preferably made thinner at the bends, as illustrated. Sets of the feed-rolls 23, 24, are positioned adjacent the delivery sides of the curved 90 guides, to pull the plies past the latter.

The completed web is fed by rolls 25 into a cross-folder 26.

If desired, the web may travel in a straight line from the adhesive applicators through the 95 drying ovens, instead of taking the illustrated tortuous path, and wedge-like separators may still be used, although they need not be curved into U form, as shown at Figure 3. Where the broad curved separators 21 are 100 employed, they may be used only at the bends in the traveling web. The separators may point alternately in opposite directions, as illustrated, to conform to the zigzag section 105 of the composite web.

Variations may be resorted to within the scope of the invention, and portions of the improvements may be used without others.

Having thus described my invention, I 110 claim:

1. The method of manufacturing a composite web for use in a typewriting machine, consisting in printing a succession of forms upon a plurality of superposed plies, assembling the plies with the forms in register, applying adhesive material to the edges of the interior plies, and pressing the side edges of said interior plies into contact with each other, one side edge of each interior ply engaging the adjacent edge of the overlying ply, the other side edge engaging the adjacent edge of the next underlying ply, and holding each two adhering edges apart from the other side edges of said plies until the adhesion on two engaging edges has hardened and is not effective to stick to the other plies.

2. The method of manufacturing a composite longitudinally fan-folded web for use 120 in a typewriting machine, consisting in 130

printing a succession of forms upon a plurality of plies, assembling said plies with the forms in register, holding said plies slightly away from each other, applying a viscous adhesive to the side edges of said plies, bringing into engagement side edges of said plies, one side edge of each interior ply engaging an adjacent side edge of another ply to adhere thereto, holding each two adhering edges separated from the other edges until said adhesive has dried and lost its stickiness, and reducing said web to a compact roll or work-pack.

3. The method of manufacturing a composite longitudinally fan-folded web for use in a typewriting machine, consisting in printing a succession of forms upon a plurality of plies, assembling said plies with the forms in register, holding said plies slightly away from each other, applying a viscous adhesive to the side edges of said plies, bringing into engagement side edges of said plies, one side edge of each interior ply engaging an adjacent side edge of another ply to adhere thereto, holding each two adhering edges separated from the other edges until said adhesive has dried and lost its stickiness, bringing said plies into a compact superposed relation, and transversely fan-folding said web to form a compact multiple-layer work-pack.

4. The combination with means for simultaneously printing a series of separate web-plies with a succession of forms, of means for assembling the plies adjacent each other with the printed forms in register, instrumentalities for applying an adhesive to the side edges of said plies, and instrumentalities for conjoining said side edges, whereby to form a composite work-web having longitudinal fan-folds.

5. The combination with means for simultaneously printing a series of separate web-plies with a succession of forms, of means for assembling the plies adjacent each other with the printed forms in register, instrumentalities for applying an adhesive to the side edges of said plies, instrumentalities for conjoining said side edges to form a longitudinally fan-folded work-web, and means for holding said conjoined edges away from other plies, whereby said viscous adhesive may dry on two engaging edges without fouling any other portion of the web.

6. The combination with means for simultaneously printing a series of separate web-plies with a succession of forms, of means for assembling the plies adjacent each other with the printed forms in register, instrumentalities for applying an adhesive to the side edges of said plies, instrumentalities for conjoining said side edges to form a longitudinally fan-folded work-web, and devices for drying said adhesive while each couple of conjoined edges is held separate from other conjoined edges.

7. The combination with means for bringing plies of a web closely adjacent each other, of means for applying a viscous adhesive to the side edges of said plies, devices for conjoining side edges of said plies, whereby to form a longitudinal fan-folded web having fan-folds slightly open, a drying oven, instrumentalities for conducting said web through said oven, and instrumentalities for holding said fan-folds slightly open, while said web is being conducted through said oven.

8. The combination with means for assembling plies of a work-web whereby the side edges of the plies are disposed adjacent each other, of means for applying a viscous adhesive to said side edges, devices for conjoining side edges of said plies in a way to form a web having longitudinal fan-folds slightly open, a drying oven, means for drying said web through said oven, and instrumentalities for holding said fan-folds open and each couple of adhering edges away from the other side edges of said plies, said instrumentalities having means effective for guiding said web along curved paths while being drawn through said oven.
